UNITED STATES PATENT OFFICE

HARRY D. SMITH, OF EAST ST. LOUIS, ILLINOIS, AND WILLARD D. SMITH, OF MAPLEWOOD, MISSOURI, ASSIGNORS TO ST. LOUIS PUMP AND EQUIPMENT COMPANY, OF ST. LOUIS, MISSOURI, A CORPORATION OF MISSOURI

DISPENSING APPARATUS

Application filed December 29, 1924. Serial No. 753,604.

This invention relates to mechanical apparatus, and with regard to certain more specific features, to filling stations.

Among the several objects of the invention may be noted the provision of simple and compact liquid-dispensing apparatus; the provision of reliable and durable means for indicating the amounts of liquid dispensed; and the provision of apparatus inexpensive in construction, accurate in operation, easily assembled and readily disassembled for inspection or repair. Other objects will be in part obvious and in part pointed out hereinafter.

15 The invention accordingly comprises the elements and combination of elements, features of construction, and arrangements of parts which will be exemplified in the structure hereinafter described, and the scope of 20 the application of which will be indicated in the following claims.

In the accompanying drawings, in which is illustrated one of various possible embodiments of the invention,

25 Fig. 1 is a front elevation showing the station in locked night drain position;

Fig. 2 is a left side elevation of Fig. 1;

Fig. 3 is a rear elevation of Fig. 1;

Fig. 4 is a perspective taken from the left 30 and front of the station when in locked night drain position;

Fig. 5 is a front elevation of the first level with certain parts broken away and the others shown in zero neutral position;

Fig. 6 is a left side elevation of the first 35 level with certain parts broken away and the others shown in zero neutral position;

Fig. 7 is a horizontal section taken on the line 7-7 of Fig. 6;

40 Fig. 8 is a horizontal section taken on the line 8-8 of Fig. 14;

Fig. 9 is a left side elevation of the third 45 and fourth levels with parts broken away and the others shown in zero neutral position;

Fig. 10 is a front elevation of Fig. 9 with parts broken away;

Fig. 11 is a horizontal section taken on the line 11-11 of Fig. 10;

50 Fig. 12 is an enlarged horizontal section of

the stop-shaft and dial in the 5 gallon drain position;

Fig. 13 is an enlarged horizontal section of the stop-shaft gears shown in zero neutral position;

55 Fig. 14 is a vertical central section taken from front to rear, chiefly on the second level showing the parts in their 5 gallon dispensing position;

Fig. 15 is a vertical central section similar 60 to Fig. 14 showing the parts in their zero neutral position;

Fig. 16 is a vertical central section similar 65 to Fig. 14 showing the parts in night drain position;

Fig. 17 is a horizontal section taken on the line 17-17 of Fig. 14 showing the parts in zero neutral position;

Fig. 18 is a horizontal section taken on the line 18-18 of Fig. 10;

70 Fig. 19 is a front view of the operating handle and hose valve shown in 5 gallon dispensing position;

Fig. 20 is a front view similar to Fig. 19 showing the hose valve closed and the night 75 drain valve closed;

Fig. 21 is a view similar to Fig. 19 showing the parts in locked night drain position;

Fig. 22 is a section of part of the operating handle taken on the line 22-22 of Fig. 20;

80 Fig. 23 is a horizontal section of the operating handle taken on the line 23-23 of Fig. 20;

Fig. 24 is a vertical section taken from right to left on line 24-24 of Fig. 15, (parts 85 shown in zero neutral position);

Fig. 25 is a vertical section similar to Fig. 24 taken on the line 25-25 of Fig. 14 showing the parts in dispensing position;

Fig. 26 is a vertical section similar to Fig. 25 taken on line 26-26 of Fig. 16, showing the parts in night drain position;

Fig. 27 is a left side elevation of the first 95 and second levels with some parts broken away and the others shown in zero neutral position, showing a modification;

Fig. 28 is a lateral vertical section of parts of levels one, two and three of the modification;

Fig. 29 is a horizontal section taken on the line 29—29 of Fig. 24.

CONSTRUCTION

In general

Referring now more particularly to Figs. 1 to 4 of the accompanying drawings, there is illustrated an apparatus, in this instance a gasoline filling station of the so-called "visible" type, comprising what may be termed a series of four sections of compartments or levels numbered 1 to 4 respectively. The first, third and fourth levels have floors, separating the level more or less completely (as the case may be) from the level below.

In the first level 1 are located the inlet and overflow pipes from and to a reservoir (not shown), the gasoline pump and drive therefor, quantity stops, a stop handle and gearing therefor and an indicating scale.

In the second level 2 is mounted the operating handle, discharge valve, discharge passage, hose, the drain valve and draining passages, the lock, and mechanism associated with these several parts.

In the third level 3 is mounted a container, quantity indicators, a surrounding protective screen, supply pipe, distributor head, overflow pipe, and an emptying weir.

In the fourth level 4 is a downwardly reflecting dome encasing electric lights, and surmounted by a translucent bulb containing an electric light and used for illuminating or advertising purposes or both.

For convenience the four levels will be considered separately.

First level (Figs. 4, 5, 6 and 7)

The base 10 is a casting having a hole 12 at each of its four corners so that the base can be attached to a floor or other surface. It has bolted forwardly thereto and on its upper surface an accessible wire junction box 14, and rearwardly the accessible L-junction castings 16 and 18 for the overflow and inlet pipes respectively.

The gasoline inlet piping 20 extends horizontally into the right rear of the machine and runs forwardly to the L 18 and thence vertically from said L, to the gasoline pump 22, then up from the discharge side of the pump, through the first and second levels and to the third. In the third level an inlet pipe I receives gasoline flow from the piping 20.

The overflow piping 24 extends horizontally into the left rear of the machine and runs forwardly to the L 16, and thence vertically from said L through the first and second levels and to the third. The overflow pipe O passes gasoline to said overflow piping 24.

The gasoline pump 22, which is preferably of the rotary type is mounted on a platform 26. This platform is clamped to the vertical

inlet and overflow pipes 20 and 24, and to the vertical wiring conduit 28 through which conduit upwardly leading wires from the junction box 14 are led. The pump 22 is hand driven by means of a set of step-up gears 30, the pinion of which is located on the pump rotor shaft. The pump shaft runs from front to rear of the machine. The driving gear of the step-up set 30 is made to turn by means of the rearwardly disposed hand crank 32, operable outside of a casing 34 which confines the parts within the first level. The casing 34 is mounted on a sub-casing 35 which last named casing encloses the junction box and L castings. The casing 34 has means for opening it, in order that the first level may be easily examined or entered for repairs. The L castings have their respective vertical pipes threaded therein and stuffing boxes 36 provided at the threaded portions. This construction permits of adjustment of the vertical pipes without consequent leakage, in so far as the stuffing boxes may be tightened after an adjustment.

A vertical brace 38 for the upper levels is housed within the casing of the first level 1.

Quantity stop rod and quantity control rod brackets

Below the pump bracket 26 and fastened to the same uprights which hold said pump bracket namely, the pipes 20, 24 and 28, is a lower horizontal bracket 40.

Above the pump bracket 26 and fastened to the pipes 20 and 24 is another horizontal bracket 42 (see Figs. 14 to 16, and 24 to 26).

The quantity stop mechanism (Figs. 5, 6, 8, 12, 13 and 24 to 26)

Between the horizontal brackets 40 and 42 in first level 1 are mounted a vertical stop-shaft 44 and a vertical control shaft 46.

The stop-shaft 44 is borne in bearings 48 and 50 of the lower and upper brackets 40 and 42 respectively.

The control shaft 46 is borne in bearings 52 and 54 of the lower and upper brackets 40 and 42 respectively.

The bearings 48, 50, 52 and 54 are of one type, comprising, (see Fig. 6), a threaded adjustable socket 56 screwed to the bracket and locked to said bracket by means of nuts 58. The socket carries the ball end 60 of the shaft borne therein.

The quantity stop shaft 44 and control shaft 46 are mounted vertically between said brackets and are geared at their lower ends by means of sector gears 62 and 64. The latter gear 64 is on the control shaft. The gears are pinned to their respective shafts. By means of the gears 62 and 64 rotation of the control shaft 46 causes opposite rotation of the quantity stop shaft 44.

The stop shaft 44 carries fastened thereon properly spaced brackets or quantity stops

0', 1', 2', 3', 4', 5', 6', 7', 8', 9', 10', spaced in sequence downwardly. In the present embodiment there are eleven stops although the number may vary to suit a given station capacity. This station will deliver a maximum of ten gallons with one filling.

The quantity stops are spaced vertically, as described. With regard to lateral spacing, each quantity stop, before fastening it to the shaft 44 in its required horizontal plane, has been rotated out of the vertical plane of the one above it. This rotation has been of such an amount as to throw the ends of the stops out of interference in vertical projection or plan. (See Fig. 12.)

The ends of the stops are provided with flat headed adjustable bolts 66, in order that wear may be compensated for, and adjustments easily made.

20 The stop shaft 44 carries thereon also a horizontal arm 68 which in turn carries the arcuate strip 70. This strip carries thereon numbers which correspond, when registering with a hole 72 in the forward side of case 25 34, with the number of gallons of gasoline being delivered or about to be delivered.

20 The control shaft 46 is provided with a longitudinally slidable shoe 74 (Figs. 5, 6 and 12). The shaft 46 is rotatable within a bearing 76 of said shoe 74. A heel 78 of said shoe cooperates with any one of the said eleven quantity stops that happens to be set in the vertical path of said heel. The shoe 74 is kept from turning by means of its fastenings (bolts 80) to a vertically slidable weir strip 82. The function of the strip 82 will be described later.

Embracing the upper and lower ends of the slidable shoe 74 are the forked portions 84 of the adjusting handle 86. The handle 86 and portions 84 are slidably mounted on the control shaft 46 but not rotatably mounted thereon. Rotation is prevented by means of a key-wheel 88 pinned within the upper forked portion 84, in such a manner as to extend into a longitudinal key-way 90 of the control shaft 46.

The adjusting handle 86 extends horizontally forward and out through a slot 92 provided in the casing 34. The lateral width of the slot 92 is such as to permit the handle 86 to take the dotted line positions *a* and *b* shown in Fig. 12. The slot 92 is of such vertical length that the handle 86 may, by means of its forked portions, be permitted to carry the shoe 74 and heel 78 past any possible point of stoppage by the stops 0', 1', 2', 3', 4', 5', 6', 7', 8', 9', and 10'. Numerals 94 beside the slot 92 indicate numbers of gallons of gasoline dispensing, or to be dispensed when the handle 86 is at a given elevation.

Second level (Figs. 14 to 17; 19 to 21 and 24 to 26 inclusive)

65 This comprises a more or less flat casting 98

on the under side of which are bolted three main castings 100, 102 and 104 (Figs. 14 and 17).

Passages and drain valve

The casting 100 is provided with a passage 106 which serves to establish communication between the overflow pipe O screwed into the top of said casting 100 (extending up into the third level) and the overflow piping 24. (See Figs. 14 to 17). The casting 100 is bolted to the casting 102 as well as to casting 98. The overflow passage 106, of casting 100, communicates by means of a branch passage 108 with a branch passage 110 of casting 102. (Fig. 17).

Between the casting 102 and the flat casting 98 is interposed a flange or plate 112 to which is fastened, by soldering or a like method, a discharge tube D. The discharge tube D passes downwardly through a passage 115 in the casting 98 and communicates with a rectangular discharge passage 116 of the casting 102. A passage 114 in the flange 112 permits this communication. (Figs. 14 to 17).

Between the casting 102 is fastened a depending casting 118 with a discharge passage 120 therein. The passage 120 communicates with the passage 116 of casting 102 and communicates with a discharge valve 122 by means of a nipple 124.

A by-pass 126 in casting 102 permits communication between the third level and discharge passage 116. In this by-pass 126 is located a drain valve 128 which is operable to make or break the by-pass communication between the third level and the discharge passage 116.

The drain valve 128 comprises a passaged guide spider 130 which guides the valve 128 to its seat when said valve is closing. Valve 128 is fastened to a valve stem 132, and when not forcibly pulled from its seat, is held closed by means of spring 134. The valve stem 132 passes forwardly of the pump and out through a self adjusting stuffing gland 136. An adjustable follower 138 is screwed to the outer end of the valve stem and locked in position by means of a lock nut. The follower 138 is provided with a disc-shaped head 140. (Figs. 15, 21 and 22).

The casting 104 (Fig. 17) has a passage 142 therein which establishes communication between the filling pipes 20 and the gasoline inlet pipe I of the third level. Both inlet and overflow pipes I and O pass through passages in the casting 98 and screw into the castings 104 and 100 respectively.

Adjustable weir blade.—Passing vertically through the casting 102 is the slidable weir blade 82 already mentioned in connection with the first level 1. This blade 82 cooperates slidably with the discharge tube D of the third level 3 and is fastened to the shoe 74 in the first level 1. By means of the shoe 130

74 the blade is raised and lowered. In passing through the casting 102 the blade is packed against leakage of gasoline by means of a stuffing box 142^a. (Figs. 14 to 15 and 24 to 26).

Stuffing box 142^a (Figs. 14 to 17 and 24 to 26)

for the weir blade comprises an elongated hole 143 through casting 102 lined with a 10 metallic spacer 144. A length of packing material 146 surrounds the blade at the upper end of the spacer 144. A beveled portion of the flange 112 prevents the packing being forced out upwardly. Beneath the packing 146 are 15 slipped flat gratings 148 whose end arms 150 embrace the weir blade. The gratings 148 are provided with openings 152. (Figs. 25 and 29). Underneath said gratings is provided another length of packing 154. The 20 purpose of the gratings is to keep an open passage thru the packing at the level of insertion of said gratings. This level coincides with the level of the branch passage 110. Below the packing 154 is a spacer piece 156. 25 This piece 156 is placed opposite a sub-passage 158 leading from the branch passage 110. Below the spacer piece 156 is placed more packing 160 and beneath this packing 160, the packing follower 162. The packing follower 30 162 is adapted, by means of studs and nuts 164, to properly force the recited elements of the stuffing box together.

The weir blade is provided with a lateral row 166 of five holes so placed that when said 35 blade is in its uppermost or "night drain" position, said holes align with the openings 152 in the gratings 148 (Figs. 16 and 26) and when said blade is in its "zero" or "neutral" 40 position said holes align with the opening provided by the spacer piece 156, (Figs. 15 and 24).

A casing 159 interposed between the casting 98 and casing 34 serves to substantially enclose the recited parts of the second level 2.

45 The lock handle H (Figs. 14 to 16, 22, 23 and 19 to 21)

comprises an approximately ring shaped casting 172, on opposite sides of which are provided handles 175 for purposes of operation. The casting 172 swings relatively on the hub 178 for a limited distance (Fig. 23). Its ring shape surrounds the discharge valve. The hub 178 is keyed to a shaft 180 and is provided 55 with a flange 182 rearwardly thereof. On the forward end of the hub is placed another flange 184 which seats on a chamfered portion of the hub and is held thereto by a nut 186 threaded to the shaft 180. The flanges 182 and 184 are 60 provided with oppositely drilled sets of holes 188 and 190 respectively spaced 180 degrees apart.

Two larger holes 194 are drilled (in positions corresponding to the recited holes) in 65 the hub portion 192 of the operating handle

casting 172. These holes 194 are each provided with two sets or pairs of balls 196. Each pair of balls has its ball members pressed apart by a spring 198, whereby all the balls press outwardly against the flanges 182 and 184. When the holes 194 of the hub 192 align with the sets of holes 188 and 190 in the flanges the balls are slightly pressed into the said holes 188 and 190, thereby causing an easily broken clutch connection between the lock handles and the shaft 180. The recited device is, in fact a light-load clutch and will be designated as clutch C hereinafter.

The shaft 180 is the pivot shaft of the discharge valve 122. This valve 122 is of the "gate" type and the shaft 180 operates the gate 200 (Figs. 14, and 19 to 21) to open and shut positions.

Therefore the handles 175 of the casting 172 will open and shut the gate valve 122 if turned clockwise and counter-clockwise respectively.

On the upper side of the casting 172 is formed a cam 202 (Figs. 19 to 22) which comprises a slot 204, guides 206 and wedge shaped 90 cam surfaces or fingers 208 sloping toward and under the head 140 of the drain valve follower 138. The enlarged head 140 of the follower is adapted to fit between the guides 206 and be pulled forwardly from its extreme "drain closed" position by means of the fingers 208 as said fingers swing counter-clockwise around the pivot shaft 180 as center. The guides 206 and the fingers 208 are integrally cast. This counter-clockwise movement incidentally closes the discharge gate valve 122. Bringing forward the follower 138 obviously opens the drain valve 128.

Beside the clutch C there is a lost motion engagement between the casting 172 and the pivot shaft 180. This comprises a pin 210 (Figs. 19 to 21) fitted to the casting 172 adapted to cooperate with either end of a relatively long notch 212 cut in the edge of the forward flange 184. When the pin cooperates with the right hand edge of said notch 212 the clutch C is engaged, (Figs. 19 and 23). When the pin cooperates with the left edge of said notch the clutch is disengaged, that is, the balls 196 are free of their holes 188, 190 and ride easily on the flanges 178 and 184.

The function of the lost-motion movement of the pin and slot is to permit the drain valve to close before the discharge valve opens during a given cycle of events. That is to say, the cam 202 has angular lead when revolved clockwise (Fig. 20). The lead given to cam 202 by the movement of pin 210 across notch 212 also closes the clutch C, (contrast Figs. 21 and 20), as well as it closes the drain valve before the discharge valve opens.

The function of the clutch C is to cause the discharge valve to close before the drain valve is opened. That is, the above described

angular lead of the cam 102 is converted to lag on the counter-clockwise movement of the handles 175 in so far as the closed clutch C holds the pin 210 against the right-hand end 5 of the slot 212 on the said counter-clockwise movement. See Fig. 20. At the end of said movement the seating of the gate valve, and continuing action of the handles 175 counter-clockwise, again opens the light-load clutch 10 C (Fig. 21).

Interlock (Figs. 14 to 16, 19 to 21, 25 and 26)

The handle casting 172 is provided on its lower side with a hole 214 which, when the 15 handles are in night or neutral position, is adapted to cooperate with a rod 216 borne slidably in depending bearings 218 and 219 of the casting 118. The rod 216 is normally held toward the rear of the pump with a 20 pinned collar 220 forced against the rearward depending bearing 218 by the spring 222 which reacts against the forward depending bearing 219. In locked position the rod 216 is pulled forward (Fig. 16) so that a hole 25 224 drilled laterally therein is brought outside of the casing 34. In this position a padlock may be locked on the rod 216 by means of hole 224, thus preventing the rod from returning to normal position. The hole in the 30 case 34 through which the rod 216 passes will not admit the padlock.

The rod 216, in viewing the pump from the rear normally interferes with the weir blade 82 at the edge thereof. A notch 226 is cut in 35 the rod, which when the rod is in discharge or zero-neutral position, will permit the weir blade 82 to move up and down. (Figs. 14 and 15). A flat faced cam 228 fastened to the 40 weir blade is adapted to hold the rod 216 in such a position as to cause it to enter the hole 214 of the handle casting and at the same time permit travel of the weir blade vertically. The cam 228 cooperates with a sloping face 230 of said rod 216. The weir blade 45 can move vertically when the rod 216 rides on the cam 228 and when said rod is pressed rearwardly in its unlocked position by spring 222. This is due to the width of the notch 226.

When the rod 216 is pulled forward and 50 into locked position in the handle casting 172, the notch 226 goes out of register with the plane of the weir blade 82 and to provide for its movement forward a notch 232 is cut 55 into the weir blade (Figs. 25 and 26). Of course the rod 216 can move forward to locked position only when the notch 232 registers with the rod 216. The notch 232 is adapted to register with rod 216 only when the weir 60 blade is in its highest position, or when holes 166 are in line with the grating holes 152.

Third level 3 (Figs. 4, 9, 10 and 24 to 26)

The container K.—The third level 3 65 comprises a glass container K seated on the floor

casting 98 with a gasket 238 interposed therebetween. Tie rods 240 cooperating with a cover 242 serve to draw and hold the container K down. One of these tie rods is hollow for the purposes of leading wires to the 70 fourth level. A transparent pane 244 is provided in the cover 242. Depending from said cover is a deflector 246. Around the container is provided a protective screen S.

The inlet pipe I, stands vertically within 75 the container beneath the deflector 246 and is screwed into the casting 104.

The overflow pipe O, stands vertically 80 within the container and is screwed into the casting 100 (Figs. 10 and 17). This pipe is made adjustable in length by means of the cap 248 screwed thereon. The cap 248 is kept aligned by the ring 250 and has its downward adjustment limited by the lugs 252. The length of this pipe is made such that it will 85 permit a level of gasoline in the container up to the zero marking of the indicators 243. (Figs. 9 and 10.)

The discharge pipe D (Figs. 18, 24 and 25)

is preferably of rectangular section and 90 stands vertically in the container K. It is soldered or otherwise fastened to the flange 112 and communicates with the discharge. Stay bolts or rods 254 are provided to keep 95 its shape. This pipe D is open along its length on one side. The opposite sides of the opening 256 are provided with babbitt lined grooves 258 within which slide the sides of the weir blade 82. The said lining may be 100 replaced by any suitable yielding material provided a seal is maintained between the weir blade and pipe D. The pipe D reaches above the level of the overflow pipe O.

The siphon-breaker SB permits, by means 105 of branch A, air to enter the container K as liquid descends therein and permits, by means of branch B, air to enter the discharge side of the discharge valve 122. (Figs. 9 and 17).

Fourth level (Figs. 9, 10 and 11)

The fourth level 4 comprises a downwardly reflecting dome 260, held up by means of the conduit 262 and bolted to the cover 242.

Wires are brought to this reflecting dome 115 as described and led to a light 264 placed centrally thereof. This light shines through the pane 244 and permits the condition of gasoline within the container K to be examined.

Lights 266 placed at the feet of the conduit 262 permit the quantity markers 243 to be viewed. The lights are opposite said markers. (Figs. 4 and 10).

Upon the dome 260 is a translucent bulb 125 268 containing centrally thereof a light 270 wired in the circuit of said lights. The bulb 268 is removably fastened by means of clamps 272. The bulb 268 serves for display purposes.

OPERATION

Night locked position (Figs. 4, 9, 16, 21 and 26)

In this position the operator is supposed to have closed the station and left it. In closing up he pulls the control handle 86 up as high as it will go. Its lateral position is now of no consequence inasmuch as the construction is such that the heel 78 of the shoe 74 can never be in a position below the quantity stops. As may be seen from Figs. 5 and 13, the limiting left-hand position of the handle 86, results in a limiting position of the stop 10' farther than which it cannot go to let the shoe under the stops. Therefore in pulling up the shoe it is always from a position above the helix formed by the succession of stops, a position below the same being impossible 20 for it to assume. The handle in rising takes with it shoe 74 and consequently the weir blade 82 is forced up to its highest position in the grooves 258 of the discharge pipe D, thereby entirely closing the length of the 25 opening 256 therein. In this position of the weir blade 82, no discharge is possible through pipe D (Figs. 9 and 26).

In night locked position the operating handle H is thrown to its extreme counter-clock 30 position C—C shown in Fig. 21, by the dotted line X thereby aligning the hole 214 with the interlock rod 216. As the weir blade is brought upwardly its cam 228 cooperates with said rod 216 to throw it forwardly into the hole 214 (see Fig. 15). During these operations the weir blade rides through the notch 226 of said rod 216.

The weir blade in its uppermost position, beside closing the discharge pipe opening, 40 has the holes 166 in said blade aligned with the holes 152 of the gratings 148 in the passage 110, thereby permitting drainage of any gasoline in the pipe D and passage 116. Drainage takes place through passage 110 45 and 106 to the overflow piping 24.

The counter-clockwise motion of the operating handle H opens the drain valve 128 by means of cams 202, (Figs. 15 and 21), thereby permitting drainage of gasoline from the 50 container K, through the by-pass 126 and thence through the holes 166 of the weir blade to the overflow piping described.

It should be noted that the drain valve 128 is caused to open after the discharge valve 55 124 closes inasmuch as the light-load clutch C when closed as in Fig. 19, tends to keep the relative positions between handles and discharge valve (shown in Fig. 19) the same until the gate 122 seats, namely until the discharge valve closes (Fig. 20). Fig. 23 shows the clutch C as closed on the counter-clockwise stroke. Then the clutch is forced open and the handles in turning further counter-clockwise open the drain valve, while pin 210 60 65 rides across the notch 212, (Fig. 21). This

timing feature prevents discharging through a partially open discharge valve while the drain valve is open. The discharge valve is positively shut before drainage begins. (Figs. 16 and 26).

The weir blade 82 in its uppermost or lock position is adapted also to align notch 232 thereof with the interlock rod 216, thereby permitting the operator to pull said rod forward, whereupon he can apply a padlock to the hole 224 therein.

All parts are now permanently held in the positions shown in Figs. 4, 16 and 26.

To recapitulate.—The lock handles H are in the position indicated by dotted line X. (Figure 21). The discharge valve is shut. The drain valve is open.

The weir blade is in its uppermost position closing the side of the drain pipe or tube D. The holes 166 in said weir blade are in line 85 with the branch passage 110. The notch 232 aligns with the rod 216, and said rod is pulled forward. The notch 226 in the rod 216 is out of register with the weir blade thereby locking said blade in night position. The rod 216 registers with and is in the hole 214 of the lock handle casting 172 thereby locking said lock handle casting in position. A padlock in hole 224 of said rod 216 prevents its springing from its locked position.

Gasoline drains from the discharge tube D through passages 114 and 116 to passages 110 and 106 by means of the holes 166 in the weir blade and holes 152 in gratings 148. The gasoline can not discharge from valve 100 122.

Neither the adjusting handle 86 nor the lock handle casting 72 can be moved. Any gasoline pumped into the container will drain back to the supply by way of the overflow piping as described.

Unlocking events.—To unlock the station the padlock is removed from hole 224 in the interlock shaft 216 with the aid of a key. The interlock shaft springs to its rearward 110 position against the cam 228 thereby aligning its slot or notch 226 with the weir blade (Fig. 15). Because of said cam 228 the shaft 216 does not quite leave its position in hole 214 of the lock handle casting 172.

The weir blade 82 is now movable vertically while the operating handles are not. Gasoline now pumped into the device will yet pass to the overflow piping 24 as described.

Filling event.—To fill the container K (Figs. 5, 6, 12, 13, 15, 19 and 24) the adjusting handle 86 (Fig. 12) is thrown to the left hand position which corresponds to such a position of the arcuate dial strip 70 as to put its number zero at the hole 72. Motion is transmitted from the control shaft 46 to the quantity stop shaft 44 by means of the gears 62 and 64 shown in Fig. 13. The motion of handle 86, described, throws the upper 125 130

- quantity stop O' into position under heel 78 of shoe 74. It can go no farther, this preventing the shoe from getting under the stops.
- 5 The handle 86 is now depressed to its zero position in its slot. (Fig. 6 and 24). It is stopped at such a position because the quantity stop O' interferes with further downward motion of the heel 78.
- 10 During the control handle's motion down to zero position the cam 228 has left contact with the interlock shaft 216 permitting said shaft to spring to its extreme rearward position. In so doing the shaft 216 leaves the hole 214 of the operating handle casting 172 thereby freeing said handles for action. The weir blade is yet movable because in register with the slot 226 in shaft 216 (Fig. 14).
- 15 In moving down with the control handle to zero position the weir blade is adapted to bring its holes 166 out of alignment with the drain passages to alignment with the spacer 156.
- 20 Filling of the container K is now accomplished by operating the gasoline pump 22 by means of the crank 32 (Figs. 6 and 7). Entering gasoline flows through the inlet piping 20, passes through passage 142, (Fig. 17), inlet pipe I and strikes the deflector 246 (Fig. 10). The container fills as does the discharge pipe D. The pipe D fills by way of the drain valve 128 (now open). Each fills with the same instantaneous series 30 of levels, forming a U-tube in effect, until the level reaches the overflow pipe. The pumping operation may then be stopped and any excess gasoline flows back to the supply by way of the overflow pipe O, passage 106 and overflow piping 24. Its level comes to the zero marker on the container and the station is ready to dispense or discharge any number of gallons of gasoline up to its ten gallon capacity. Substantially no liquid can pass 40 to the overflow by way of the branch passage 110 in so far as the holes 166 of the blade are in line with passage 158. Their function now is to permit that small amount of gasoline which leaks past packing 154 to enter 45 the overflow piping by way of passage 106. This prevents gasoline from dripping down into the lower pump parts.
- Discharge event*
- 55 A given number of gallons may be dispensed by turning control handle 86 laterally until the given number, say five, appears at the hole 72 (on the arcuate dial 70). This operation puts the quantity stop 5' in a vertical line with the heel 78 of the shoe 74. Now, upon depressing the handle 86 it will be stopped at its position five, showing that five gallons are to be dispensed. The friction in the mechanism is great enough to eliminate 60 too great a sensitiveness such as might result in a tendency of the handle 86 to rotate as it is depressed. Furthermore such rotation, if enough to throw the predetermined stop out of line would be detected due to the fact that the handle would stop at the wrong numeral 94 marked on the case. 70
- The weir blade is now lowered in its grooves and the discharge pipe D is open for a part of its length corresponding to a discharge of five gallons. The cam 228 is 75 now clear of the interlock rod 216 which rod is now in its extreme rearward position and out of the hole 214 of the handle casting 172. The slot in said rod remains in alignment with the weir gate or blade. 80
- The operating handles 175 may now be thrown clockwise from the dotted line position X shown in Fig. 21 to the dotted line position Y shown in Fig. 19, thereby first, closing the drain valve 128 and second, opening the discharge valve 122, as described. When the handle is on the line Z shown in Fig. 20, the drain valve is closed, but a movement of the handle 175 in a clockwise direction will open the discharge valve 122. Gasoline now flows over the weir gate 82 down the discharge pipe D, through passages 114, 116 and 120, through the open discharge valve 122 and into a suitable discharge hose to the customer's tank. This continues until the level of the gasoline reaches the top of the weir gate or blade 82 and the discharge passages are empty. 95
- The lower arcuate portion of the casting prevents, by means of the interlock rod 216 and cam 228, the pulling up of the weir blade to night drain position. This is because the rod 216 cannot come forward. Likewise the head 140 of the drain valve cannot be pulled forward to drain, because of its riding under an upper arcuate portion of said casting 172. This prevents returning to the supply gasoline which supposedly is going to the customer. 100
- The operator next turns the handles back to their neutral position (dotted line X Fig. 21), thereby closing the discharge valve before the drain valve is opened as before described. 105
- When the operating handles are back in neutral position (dotted line X Fig. 21) the drain valve 128 is again opened so that the conditions which held before discharge are reestablished and the reading for the level of the gasoline at the quantity markers 243 on the glass container K represents the true quantity discharged or dispensed or both. 115
- From the last named five gallon position of the parts, another setting may be made for more gasoline to be discharged, if proper settings are made for a quantity in excess of that set for at first. This is of advantage when a customer finds he can use more gasoline than he first supposed. The settings are 120 125 130

made in the sequence and manner already described.

Return to filling event

5 The operating handles are thrown to neutral position (dotted line X Figs. 21 and 14) or are already there. Then the control handle is drawn upwardly to its upper position and turned clockwise (Fig. 12). This brings number zero of the dial 70 to hole 72 and quantity stop O' under the heel 78. Depression of the control handle causes the heel to again strike the stop O'. Now the cam 228 again is in contact with the rod 216, 10 and said rod has entered hole 214 of the operating handle casting 172.

15 Filling of the container by means of the pump may now be accomplished and after overflow takes place, the gasoline level is at its zero level in the container. The pump 20 may be left in this condition until a customer arrives and the operation described is to be repeated.

MODIFICATION

25 In Figures 27 and 28 is shown a modification of the station in which all possible leakage from the packing gland for the weir blade is prevented.

30 This is accomplished by fastening a depending liquid tight casing 280 beneath the casting 102. This casing 280 is adapted to receive the weir gate or blade 82 when in its downward positions. The weir blade has had 35 the handle mechanism removed therefrom.

Should the gland for the weir blade leak, the leakage will enter this casing 280 thereby filling the same. Depression of the blade into the casing forces gasoline therefrom 40 through a small passage P placed in the said packing gland spacer 144. It enters the passage 158 and returns to the supply as described.

The control shaft 46, operable in conjunction with the quantity stop shaft 44, has been removed from its former position, slightly forwardly. This is done by moving the bearings 56.

50 The control handle 86 is operable on the control shaft as before and the mechanism associated therewith is the same. The shoe 74 however is now fastened to a round rod 282 which extends upwardly into the discharge tube D by way of a conventional stuffing gland 284 and the discharge passage of the casting 102.

55 At its upper end, within the discharge tube, it is fastened to the weir blade 82 by means of a threaded portion and lock nut 286.

60 Thus the weir blade, as before, is operable by means of handle 86 but any leakage from the round stuffing gland 284 is much more easily prevented than it is from the former flat stuffing gland for the weir blade.

65 A forked cam 288 fastened to the forward

side of the vertical rod 282 is now operable to throw the rod 216 forwardly to interlock position. This it does by cooperating with a collar 290 fastened to the rod 216.

The bearing 218 has been moved forwardly 70 to make way for the round stuffing gland 284.

A notch 292 in the vertical rod 282 cooperates with a notch 294 of the interlock rod 216 to bring about the sequence and combinations of events hereinbefore described.

75 In view of the above, it will be seen that the several objects of the invention are achieved and other advantageous results attained.

80 As many changes could be made in carrying out the above constructions without departing from the scope of the invention, it is intended that all matter contained in the above description or shown in the accompanying drawings shall be interpreted as illustrative and do not in a limiting sense.

85 We claim:

1. In a gasoline dispensing station in combination a container, means for filling said container and an overflow therefor, means for discharging the contents of said container, said means comprising an open sided tube and a blade for slidably closing said open tube from below, a discharge valve, and operable means for operating said valve, a drain for the container, a valve in the drain, means for opening the valve actuated by said hand-operable means for operating the discharge valve, and openings in said blade adapted to align with the drain.

90 2. In a gasoline dispensing station in combination a container, means for filling said container, an overflow therefor and a gated pipe comprising a gate and pipe for discharging the contents of said container, a gate valve, a conduit connecting said pipe and said valve, means for operating said valve, a drain valve for said container operable to drain and to pass liquid to said pipe, a cam on said gate valve operating means adapted to open said drain valve to drain position after said gate valve is closed, thereby causing one liquid level in both said gated pipe and container.

- overflow when said gate is in highest position and the discharge valve is closed.
4. In a gasoline dispensing station the combination of a container, means for filling and discharging said container, said discharging means comprising a discharge tube having an elongated opening therein and a slidable gate therefor, and means for adjusting the position of said slidable gate.
5. In a gasoline dispensing station the combination of a container, means for filling and discharging said container, said discharging means comprising a discharge tube and a slidable gate therefor, means for adjusting the position of said slidable gate, means for selectively limiting said position, said last-named means comprising a series of movable stops for arresting a downward movement of said gate adjusting means.
6. In a gasoline dispensing station the combination of a container, means for filling and discharging said container, said discharging means comprising a discharge tube and a slidable gate therefor, means for adjusting the position of said slidable gate, means for selectively limiting said position, said last-named means comprising a series of movable stops for arresting a downward movement of said gate adjusting means, means for indicating at what point said gate is to be arrested and means for indicating where it is actually arrested.
7. In a gasoline dispensing station the combination of a container, means for filling and discharging said container, said discharging means comprising a discharge tube and slidable gate therefor, a slidable handle cooperating with said gate, extension means associated with the handle, rotatable stops adapted to selectively stop descent of said extension means and handle and said gate, means cooperating between said handle and said stops for setting the stops in position to predeterminately stop the descent of said handle, means for indicating a given setting of the selective stops, and means for indicating the position of said handle.
8. In a gasoline dispensing station the combination of a container, means for filling and discharging said container, said discharging means comprising a discharge tube and slidable gate therefor, a slidable handle, means joining the handle and gate whereby they move up and down with one another, a vertically movable extension associated with the means joining the handle and gate, rotatable stops adapted to selectively stop descent of the handle and joining means and gate by engaging said extension, so as to position said gate, means cooperating between said handle and said stops for setting the stops in position to predeterminately stop the descent of said handle, means for indicating a given setting of the selective stops, means for indicating the position of said handle, and indicating means on said container for reading directly thereon the amount of gasoline dispensed after discharge.
9. In a gasoline dispensing station in combination a container, means for filling said container and an overflow therefor, means for discharging the contents of said container, said last named means comprising a tube having an elongated opening on at least one side and a blade for slidably engaging said opening.
10. In a gasoline dispensing station in combination a container, means for filling said container, an overflow therefor and a gated pipe comprising a gate and pipe for discharging the contents of said container, a gate valve, a conduit connecting said pipe and said valve, means for operating said valve, a drain valve for said container operable to drain, and to pass liquid to said conduit, a cam on said gate valve operating means adapted to open said gate valve to drain position after said gate valve is closed, thereby causing one liquid level in both said gated pipe and container, an opening in said conduit receiving drainage from said drain valve by way of said conduit, said opening communicating with a reservoir and openings in said gate of said pipe adapted to align with said opening in the conduit to drain liquid to the reservoir when the gate is in a predetermined position.
11. In a gasoline dispensing station, the combination, a container, means for filling said container and an overflow therefor, means for discharging the contents of said container, said means comprising a tube having a slotted side and a blade for closing said slotted side, a discharge valve and hand operable means for operating said valve, a conduit connecting said open sided tube and said discharge valve, a drain for the container, a valve in the drain, said valve when open permitting communication between the drain and the conduit, an opening in said conduit leading to the overflow, said opening being intercepted by said blade and openings in said blade adapted to register with the opening to the drain.
12. In a gasoline dispensing station, the combination, a container, means for filling said container and an overflow therefor, means for discharging the contents of said container, said means comprising a tube having a slotted side and a blade for closing said slotted side, a discharge valve and hand operable means for operating said valve, a conduit connecting said open sided tube and said discharge valve, a drain for the container, a valve in the drain, said valve when open permitting communication between the drain and the conduit, an opening in said conduit leading to the overflow, said opening being intercepted by said blade and openings in said

blade adapted to register with the opening to the drain and means associated with the hand operable means preventing setting of said blade to its draining position when the container is discharging.

5 In testimony whereof, we have signed our names to this specification this 27th day of December, 1924.

HARRY D. SMITH.
WILLARD D. SMITH.
